UNITED STATES PATENT OFFICE.

HENDRIK JOHANNES VAN DER BIJL, OF NEW YORK, N. Y., ASSIGNOR, BY MESNE ASSIGNMENTS, TO WESTERN ELECTRIC COMPANY, INCORPORATED, A CORPORATION OF NEW YORK.

THERMIONIC AMPLIFIER AND RECTIFIER.

1,193,206.

Specification of Letters Patent.

Patented Aug. 1, 1916.

Application filed September 1, 1915. Serial No. 48,525.

To all whom it may concern:

Be it known that I, HENDRIK JOHANNES VAN DER BIJL, a subject of the King of Great Britain, residing at New York, in the county of New York and State of New York, have invented certain new and useful Improvements in Thermionic Amplifiers and Rectifiers, of which the following is a full, clear, concise, and exact description.

This invention relates to detectors or amplifiers of the audion type having high current output, and its object is to render the filament of such tubes more durable.

In thermionic amplifiers and rectifiers of the audion type, the closeness of the input or grid electrode and filament to each other is important in determining the efficiency of operation. Furthermore, the distance of the output electrode from the filament and the amount of obstruction the input electrode or grid offers between the filament and output electrode are factors having a bearing on the current output of the audion.

It has been found desirable for certain types of the amplifiers or rectifiers to have the filament in the same or approximately the same plane as the grid. It has, however, been found that in such tubes, as shown in United States Patent 1,130,042, great difficulty is experienced due to breakage of the heated filament. This is caused by undue tension being applied to the filament by the supporting springs, unless the greatest care be exercised in manufacturing the tube. This invention affords a means for doing away with these springs and substituting a means of support which is much easier to use, subjects the filament to less stress, and still permits bringing the filament and grid in substantially the same plane for the purpose cited above. This means consists of insulating material carried by the grid, and which insulating material supports the filament.

Referring to the drawing, Figure 1 shows a view in perspective of a vacuum tube with the supported filament; Fig. 2 is a detailed view of a modification.

In the drawing, 3 represents the usual containing vessel which is evacuated to a high degree.

4 represents a double output electrode.

5 shows a suitable support for suspending the grid 6. Threaded through the grid are two mica strips 7 in which strips are placed

suitable holes, through which is threaded the filament 8. Suitable electrode connections 9 are run through the base of the supporting member 5 by means of which contact may be made with the various electrodes 60 in the tube.

The arrangement of the elements above described permits the filament to be in substantially the same plane as the grid, and at the same time supplies a support for the 65 filament which is easy to manipulate in manufacture and avoids the difficulty caused by undue tensions upon the said filament. For symmetry it is desirable that the same amount of filament surface shall be exposed 70 freely to each of the members 4 of the output electrode. Care should, therefore, be taken to so thread the filament through the mica strips that there will be the same number of longitudinal sections 10 facing each 75 of the plates 4. In some cases it is desirable to construct a tube of high voltage output. In this case it is found that the grid should be of a finer mesh and the distance between the grid and the filament should be 80 smaller. It is not desirable, however, to have the filament strands too close together, and in such a case the modification shown in Fig. 2 may be used. In said modification, 85 11 shows the grid, 12 shows the mica strips threaded through in such a manner that wherever the filament crosses a member of the grid, it is separated and insulated therefrom by the mica strip. It is obvious that insulating material other than mica may be 90 used without departing from the spirit of this invention. It is also obvious that the mica strips or other insulating material can be supported by the grid in other ways.

What is claimed is:

1. In a thermionic amplifier of the audion type, a grid; mica strips supported thereby and a filament supported by said strips and insulated from the grid.

2. In a thermionic amplifier of the audion type, a grid; insulating material supported thereby and a filament threaded through said insulating material, whereby the filament is supported by and brought into close proximity to said grid but insulated therefrom.

3. In a thermionic amplifier of the audion type, a grid; insulating material threaded into said grid and a filament threaded through said insulating material, whereby 110

the filament is supported by and brought into close proximity to said grid but is insulated therefrom.

4. In a thermionic amplifier of the audion type, a grid; mica strips threaded into said grid and a filament threaded through said mica strips, whereby the filament is supported by and brought into close proximity to said grid but is insulated therefrom.
5. In a thermionic amplifier of the audion

type, the combination of a grid; a double electrode facing each side of the grid; mica strips threaded into grid and a filament threaded through said mica strips in such a manner that an equal amount of filament ¹⁵ surface is exposed to each plate surface.

In witness whereof, I hereunto subscribe my name this 27th day of August A. D., 1915.

HENDRIK JOHANNES VAN DER BIJL.
